UNITED STATES PATENT OFFICE.

ARNO ARTHUR EWALD, OF OAKFIELD, WISCONSIN.

MOTOR-DRIVEN AUTOMATIC PRESSURE COIN-CONTROLLED AIR STATION.

Application filed March 7, 1921. Serial No. 450,286.

To all whom it may concern:

Be it known that I, ARNO A. EWALD, a citizen of the United States, residing at Oakfield, in the county of Fond du Lac and 5 State of Wisconsin, have invented certain new and useful Improvements in Motor-Driven Automatic Pressure Coin-Controlled Air Stations; and I do declare the following to be a full, clear, and exact description of 10 the invention, such as will enable others skilled in the art to which it appertains to make and use the same.

My invention relates to improvements in air service stations for use in the inflation 15 of automobile and other vehicle tires and has for one of its objects to generally improve upon the construction shown by my pending U. S. applications, Serial No. 357,475 and Serial No. 418,497, filed Feb. 9, 1920, and 20 October 21, 1920, respectively.

A further object of the invention is to provide a novel arrangement of parts for preventing the passage of air through the inflation hose until a nickel or other coin is 25 inserted in a slot.

A still further object is to provide for operating the station without the necessity of inserting a coin whenever desired.

A still further object is to provide an air 30 service station completely contained in a single unit so that it may be quickly and easily installed wherever desired, without the necessity of making numerous alterations in side-walks, garages, or other old parts in 35 connection with which the device is to be used.

With the foregoing and minor objects in view, the invention resides in the novel construction, combination, and arrangement of 40 parts, hereinafter described and claimed, the descriptive matter being supplemented by the accompanying drawings.

Figure 1 is a vertical sectional view, partly in elevation, showing a complete air service 45 station constructed in accordance with this invention.

Figure 2 is an enlarged sectional view partly in elevation, illustrating more particularly the coin-controlled air valve.

Figure 3 is a sectional view as indicated 50 by the irregular line 3-3 of Fig. 2.

Figure 4 is a vertical sectional view taken on the line 4-4 of Fig. 2.

In the drawings above briefly described, 55 the numeral 1 designates a vertically disposed metal casing which is preferably of

cylindrical form, being provided with a sheet metal wall, with a cast metal bottom ring 2, and with a cast metal top 3, said bottom and top being tied together by stay-bolts 4. Within the casing 1, is a compressed air tank 5 which is supplied with air through piping 6 from a motor driven air compressor 7, controlled by an automatic pressure actuated switch 8 of well known form. The wiring 9 for supplying current to the motor driven compressor is preferably passed through a vertical pipe 10 within the casing 1, as is also the wiring for an electric light 60 yet to be described.

The compressor 7 is mounted on the top casting 3 of the casing 1 and around said compressor, is a casing wall 11 which may have a suitable door (not shown) for giving access to internal parts. A suitable number 75 of vertical legs 12 are positioned adjacent the wall 11 and rise from the top casting 3 of the casing 1, the lower ends of said legs being preferably secured in place by threading the stay-bolts 4 into the same. These 80 legs support a top casting 13 which may be secured thereby by screws or the like 14, and said casting 13 forms the upper end of a hollow base constituted by the casings 11 and 1, said base serving not only to contain the air 85 tank 5, the compressor 7, and associated parts, but acting also to contain the coin-controlled valve which normally prevents the use of the station, as will be set forth 90 fully below.

Rising from the top casting 13 is a tubular standard 15 and a suitable head 16 is swivelled or otherwise mounted on the upper end of said standard, said head preferably carrying a globe 17 in which is located an electric light 18 for use at night. The head 16 carries a vertically swinging tubular arm 19 through which a rubber hose 20 passes, and from which said hose depends, the free end of this hose being provided with the usual or any preferred form of inflation valve 21 which is normally held above the ground by the arm 19. The hose 20 leads upwardly from a suitable air control valve 22 located in the upper portion of the hollow base, the portion of said hose between the valve and the arm 19, being located in the tubular standard 15. Where the hose enters the inner end of arm 19 and where said hose leaves this arm, wire coils 23 are preferably 100 employed to prevent abrupt bending and 105 injury.

For the purpose of normally raising the arm 19, any suitable counterbalancing means may be employed, but I have shown a coil spring 24 in the standard 15, the upper end 5 of said spring being connected to the inner end of the arm 19 through the instrumentality of a rod 25, while the lower end of said spring is anchored preferably by hooking the same into the lower end of a conduit 10 26 which rises through the standard 15 and carries the electric light 18, said conduit receiving the current supply wires for said light. Another vertical rod 27 is connected to and depends from the inner end of the 15 arm 19, the lower end of said rod being located in the upper portion of the hollow base and being instrumental in releasing the coin-controlled means which operates to open the normally closed valve 22. This 20 valve, as will be seen from Fig. 1, is located in a pipe line 28 leading from the compressed air tank 5, said line being preferably provided with a suitable pressure gage 29.

25 When the hose 20 is pulled downwardly, with the valve 22 opened, it may be used for inflating tires, and when released, the spring 24 will return the parts to their initial positions, and for the purpose of preventing such parts from moving so rapidly as to be injurious to the entire machine when they are brought to a standstill, I preferably use a dash-pot or other shock absorbing device 30 suitably connected with the arm 19.

35 The valve 22 above mentioned, is secured by a J-bolt or any other suitable fastener 31 to a vertical supporting plate or bracket 32 which is here shown detachably connected with the casting 13, by means of screws 33, 40 said bracket being provided with a guide sleeve 34 slidably receiving the lower end portion of the rod 27 as clearly shown in Fig. 2, said rod being instrumental in releasing the latch mechanism which is employed 45 for holding said valve 22 in open position when it is once opened through the medium of coin controlled means to be described. In the present showing, the valve 22 is provided with an operating plunger 35 to which 50 is connected a handle 36 in the form of a lever, one end of this lever being fulcrumed at 37 to the body of the valve, while its other end is outwardly curved and positioned at the lower end of a coin chute 38 with which 55 the bracket 32 is provided. Either internal mechanism of the valve 22 or a coiled spring 39 acting on the handle 36 serves to normally close the valve and position the outer end of the lever in the manner shown in Fig. 2.

60 When a nickel or other coin is dropped into the chute 38, it lodges against the end of the handle 36 and is then in the path of a spring-retracted plunger 40 so that when this plunger is pushed inwardly by hand, the coin 65 will force the handle 36 toward the valve

casing, thereby opening the valve to allow air pressure to escape from the tank 5 through the piping 28 and hose 20. The moment the handle 36 is moved in this manner, a latch comes into play to hold said handle against return movement, and it will thus be seen that when the plunger 40 is released, the coin will drop into a suitable receptacle and the valve will be held open to permit the necessary amount of air to be 75 used.

The latch above referred to is preferably in the form of a substantially horizontal lever 41 loosely fulcrumed on a bolt or the like 42 carried by the lower portion of the 80 bracket 32, one end of said lever 41 being positioned under the guide 34, while the other end of said lever is provided with a cam surface 43 and a shoulder 44 at the inner end thereof, a pin or the like 45 on the 85 handle 36, being normally in contact with the surface 43 as shown in Fig. 2, so that when this handle is moved to the left by a coin, the pin will catch behind the shoulder 44 and hold said handle in a position to 90 retain the valve open. A coil spring 46 is preferably connected with the lever 41 to engage its shoulder 44 with the pin 45 and to normally position said lever substantially as shown in Fig. 2. With the parts in these 95 relative positions, the arm 19 is raised and the rod 27 extends downwardly to the maximum, the lever 41 then passing across said rod as shown in Fig. 2. When however the 100 hose 20 is pulled downwardly for use, the arm 19 raises the rod 27 to a point above the lever 41 and a suitable spring 47 then forces said lever inwardly toward the bracket 32 so that its inner end is positioned under the 105 guide 34 in position to be struck by the rod 27 when it again moves downwardly, said lever then resting against a suitable guide finger or the like 48 which may well depend from the guide 34 as shown in Figs. 2 and 4.

After inflation, the hose 20 is released, 110 and the arm 19 returns to its initial position, thereby forcing down on the rod 27 and causing said rod to strike the lever 41 as disclosed in Fig. 4, with the result that said lever is rocked to release its shoulder 44 115 from the pin 45, causing the spring 39 or other means provided for the purpose, to automatically close the valve 22 and prevent further passage of air from the tank 5. As the end of lever 41 is moved downwardly 120 by rod 27, said end strikes an inclined cam 49 which is secured to the bracket 32, said cam serving to laterally shift the lever out of the path of rod 27 so that the latter may move downwardly to the maximum without 125 injuring the latch or other parts. As soon as the lever 41 is disengaged from rod 27, the spring 46 returns said lever to the position shown in Fig. 2 so that it will be again in readiness for operation.

If it is desired, for any reason, to permit operation of the air station without inserting the coin, the valve 22 may be locked in open position by engaging the pin 45

5 with a supplemental shoulder 50 on the upper edge of the latch lever 41, this being done by hand. When the lever 41 is used for this purpose, its inner end is positioned at one side of the guide 34, approximately 10 as shown in dotted lines in Fig. 4, being held in this position against the action of the spring 46, by a suitable spring keeper 51 which is by preference formed as an extension of the spring 47.

15 The operation of the machine, in detail, is as follows: With the parts standing as shown in Figs. 1 and 2, a coin is inserted in the chute 38 and is received between the lower end of the handle 36 and the plunger

20 40 as shown in Fig. 2. An inward push of this plunger now swings the handle 36 inwardly and opens the valve 22, simultaneously engaging the pin 45 with the shoulder 44 to hold said valve in open position against the tension of the spring 39.

25 Thus, when the hose 20 is pulled downwardly, it may be used for inflating tires and it will be seen that this downward pull will cause arm 19 to shift rod 27 upwardly above the latch lever 41. The parts remain in

30 35 this relation as long as the hose is in use, but when this hose is released and arm 19 returns toward its raised position, rod 27 is shifted downwardly with the result that it strikes lever 41 and releases the handle 36, permitting spring 39 to close the valve 22. Immediately after releasing the handle 36, the lever 41 is disengaged from the rod 27 by means of the cam 49 and said rod then 40 moves downwardly to the necessary extent while the spring 46 rests the latch lever 41 for future operation.

45 Whenever the station is to be used free of charge, pin 45 and shoulder 50 are interengaged so that the valve 22 is held in open position, the inner end of lever 41 being then held by the spring keeper 51 as shown in Fig. 4, so that it is entirely out of the downward path of rod 27 and consequently 50 cannot be tripped to release the handle 36.

55 From the foregoing, it will be seen that a very simple, compact and reliable air supply station has been devised. The mere insertion of a coin and pushing of the plunger 40 places the device in condition for use and when the hose 20 is pulled downwardly and the valve 21 applied to a tire valve, the tire may be quickly inflated. The arm 19 may swing horizontally on account of the 60 swivelled mounting of the head 16 and consequently the hose may be advantageously positioned for inflating any tire of an automobile without moving the latter. Whenever in the air in the tank lowers beyond 65 a predetermined pressure, the pressure-con-

trolled switch 8 closes the circuit of the compressor-driving motor on top of the tank 5, thereby replenishing the supply of air.

Since excellent results are obtainable from the details shown and described, such details may be followed if desired, but within the scope of the invention as claimed, numerous changes may be made and I do not therefore wish to be restricted to the exact disclosure of this application.

I claim:

1. An air supply station comprising a movable member carrying an inflation hose, a self-closing valve for normally preventing passage of air through said hose, coin-controlled means for opening said valve, a latch co-operable with the valve for holding said valve open, and means for automatically releasing said latch when said hose carrying member returns to its initial position after use of the hose.

2. An air supply station comprising a normally raised arm carrying an inflation hose and adapted to swing downwardly when said hose is to be used, a valve for normally preventing passage of air through said hose, coin-controlled means for opening said valve, and means for automatically closing said valve upon return of said arm to its raised position.

3. An air supply station comprising a normally raised arm carrying an inflation hose and adapted to swing downwardly when said hose is to be used, a valve for normally preventing passage of air through said hose, coin-controlled means for opening said valve, a latch for holding the valve in open position, and means for releasing said latch automatically when said arm returns to its raised position.

4. An air supply station comprising a hollow standard, a normally raised hose carrying arm pivoted on the upper end of said standard and adapted to swing downwardly when the hose is to be used, a rod connected with said arm and movable vertically by the swinging thereof, a coin controlled valve for normally preventing passage of air through the aforesaid hose, and means controlled by said rod for effecting closing of said valve when the aforesaid arm swings upwardly.

5. An air supply station comprising a hollow standard, a normally raised hose carrying arm pivoted on the upper end of said standard and adapted to swing downwardly when the hose is to be used, a rod connected with said arm and movable vertically by the swinging thereof, a coin controlled valve for normally preventing passage of air through the aforesaid hose, and a latch for holding said valve opened, said latch having a portion co-operable with the aforesaid rod to release said latch when

aforesaid arm swings upwardly, permitting the valve to close.

6. An air supply station comprising a movable hose carrying member, a rod connected with said member, a valve for normally preventing passage of air through said hose, coin controlled means for opening the valve, and a latch lever for holding said valve open, a part of said latch lever being in the path of said rod to be released thereby when the aforesaid member returns to its initial position.

7. A structure as specified in claim 6, together with means for shifting said latch lever from engagement with said rod when said lever is released.

8. A structure as specified in claim 6, together with a fixed cam for shifting said latch lever from engagement with said rod when said lever is released.

9. A structure as specified in claim 6, together with a fixed cam for shifting said latch lever from engagement with said rod when said lever is released, and spring means tending to shift said lever in a direction opposite to that in which it is moved by said cam.

10. A structure as specified in claim 6, together with means for holding said latch lever in effective position and out of the path of said rod if desired.

11. A structure as specified in claim 6, together with a fixed cam for shifting said latch lever out of engagement with said rod
35 when said lever is released, and a double acting spring device having a tendency to move said latch lever in a direction opposite to that in which it is moved by said cam, and also active to hold said latch lever
40 in an effective position out of the path of said rod.

12. An air supply station comprising a vertically elongated hollow base, an air tank in said base, a tubular standard rising from said hollow base, a normally raised arm mounted on said standard and carrying an inflation hose, coin-controlled means in said hollow base for controlling the discharge of air from said tank, and communicating means in said hollow standard between said last named means and said hose.

13. An air supply station comprising a standard, a swinging arm mounted on said standard, a tire inflating hose depending from said arm, a hollow base from which

said standard rises, a compressed air tank in said base, coin-controlled communicating means between said tank and hose, and a pressure-controlled motor driven compressor mounted within said hollow base on top of 60 said compressed air tank for automatically maintaining a predetermined pressure in said tank.

14. An air supply station comprising a hollow base and a standard rising therefrom, a self-raising arm pivoted to said

from, a self raising arm pivoted to said standard, an inflation hose suspended from said arm and adapted to be pulled downwardly with said arm for use as an air sup-

wardly with said arm for use, an air supply tank for said hose located in said base, 70 a bracket mounted in the upper portion of said base, and a flexible hose connected

said base, a valve mounted on said bracket for normally preventing discharge of air through said hose, coin-controlled means on

said bracket for opening said valve and holding it open, and means for automatically releasing the valve-holding means and

15. A structure as specified in claim 2 to 80 closing the valve when the hose is released and the arm returned to its initial position.

23. A structure as specified in claim 2, together with means for taking the valve out of the control of said coin-controlled means and holding it open to furnish "free air."

and holding it open to furnish "free air" whenever desired.

station having an inflation hose, and a coin controlled valve for normally preventing passage of air therethrough; of means for taking the valve out of the control of said coin-controlled means and holding it open 90 to furnish "free air" whenever desired.

17. The combination with an air supply station having an inflation hose, and a valve for normally preventing passage of air

for normally preventing passage of air therethrough; of an operating member for said valve, means for guiding a coin against said operating member, and means for

said operating member and thrusting on the coin to actuate said member and open said valve, means for holding the valve in

open position and for permitting closing thereof when the desired amount of air has been used, and means for preventing return 100

of said operating member to valve-closing position and operative relation with said coin guiding means, whereby "free air" may 105

In testimony whereof I have hereunto set my hand.

ABNO ARTHUR EWALD
